MEANS FOR LUBRICATING AND COOLING
ENGINE VALVES

William B. Ullrich, Reading, Pa.

Application November 9, 1935, Serial No. 48,966

10 Claims. (Cl. 184—6)

My invention relates to internal combustion engines employing reciprocative valves of the poppet type for controlling the fuel inlet to the cylinders and the discharges therefrom; and more particularly it relates to improved means for automatically lubricating and cooling the exhaust valves controlling the discharges of the hot burned gases.

In the operation of the conventional four cycle engine, the exhaust valves receive scanty lubrication even though the ends projected beyond their guide bearings be provided with a liberal supply of oil or oil mist, due to the pressure of the hot exhaust gases of combustion entering the guide bearings below the valve head and opposing adequate entry at the opposite end of said bearings of the oil supplied to the reciprocated projecting valve stems. And while portions of the exhaust valve stems and their guide bearings adjacent their valve heads receive some lubricant deposit from the passing exhaust gases in the form of incompletely consumed fuel constituents and partially burned oil that leaked past the piston rings, due to lack of any means for removing this deposit while mobile, subsequent exposure to the hot exhaust flames builds up this deposit into a gummy, tenacious film, forming eventually a hard tough carbon residue, retarding free action of the valve, and causing it finally to stick in partial or fully opened position, resulting in burning of the valve head and seat, complete valve failures, and costly damage to the cylinder block and head.

I am aware that attempts have heretofore been made to lubricate and cool the exhaust valves of internal combustion engines, one such means employing pump or blowers to force oil or oil mist into the guide bearing for the valve stem and through the latter to impinge against the valve head and then to be passed-off through the usual exhaust manifold and muffler. Such means has the inherent disadvantage of requiring additional working parts, and is likely to quickly result in defective valve operation by the formation of the before mentioned tough carbon residue in the exhaust passageways and extending through the entire exhaust line including the manifold and muffler, requiring frequent costly disassembling and cleaning, besides causing unnecessary and excessive smoke discharge to the atmosphere due to the burning oil.

Other attempts at cooling, employing a jet of air introduced through a hollow stem, or other means, to strike against the valve head, also requires additional working parts, and, as the valve heads of modern engines often operate at red

hot heat, and the air jet carries oxygen, such jet tends to intensify the hot flame of the exhaust gases and soon results in rapid oxidation and scaling of the valve head and stem and adjacent parts which quickly causes valve failure.

Recognizing the need of better lubrication and cooling of the exhaust valves of internal combustion engines, it is the object of my present invention to provide novel and improved means for supplying lubricant to the exhaust valve stem and its guide bearing, automatically and without the need of auxiliary equipment or power driven working parts, by utilizing solely the intake suction developed by the pistons reciprocating in their cylinders. Furthermore my objects are to insure an adequate and desirably controlled supply of lubricant entering said stem guide bearing so as to form an oil film therein between said stem and bearing for free reciprocative movements of the valve; to act as a heat conductor between said stem and guide bearing in facilitating cooling the valve; to provide an oil seal preventing exhaust gases passing through the guide causing lubricant contamination; to furnish additional oil deposit on the valve stem and guide bearing adjacent the valve head and remove the same while in a mobile state; and to insure a constant supply of fresh oil as the film within the bearing is weakened or broken down by service and heat.

With the above objects outlined, and with other objects and advantages that will be developed later herein, my invention comprises the improved engine construction and the new method or system of its automatic exhaust valve lubrication and cooling operation more fully described in connection with the accompanying drawing, and the novel features thereof are specifically set forth in the appended claims.

Fig. 1 is a sectional elevation indicating the aligned valves for two adjacent cylinders of a conventional four cycle L-head type of internal combustion engine, other engine parts being omitted as of usual known construction and not essential to a full disclosure of my invention, a prepared embodiment of which is disclosed in connection with this valve showing.

Fig. 2 is a fragmentary sectional elevation through the cylinder of another conventional type of engine, showing my invention applied to the overhead valves thereof.

Fig. 3 is a similar sectional elevation of a so-called F-head type of engine, showing my invention applied to its valve construction.

Fig. 4 shows a sectional elevation of a guide bearing for the stem of a usual poppet valve, em-

bodying construction particularly applicable to my invention.

The construction and operation of four cycle internal combustion engines is well known and 5 needs no description or showing, and in the L-head type disclosed in Fig. 1, I have indicated only the combustion chamber extensions 10 and 10' for two adjoining cylinders, and the valves mounted in the cylinder block 2, controlling the 10 opening and closing of intake passageway 3, and exhaust passage-ways 4, 4', to said chambers 10 and 10' formed in the cylinder head 5.

Two inlet valves 5, 5' are indicated having stems 6, 6' respectively, mounted in guide bearings 7, 7', with usual springs 8, 8' and tappets 9, 9' to operate the valves in known timed relation to admit a charge of combustible mixture at each cylinder intake suction stroke to either extension 10, or 10' from passage-way 3 fed by a 15 usual inlet manifold in well known manner. Two exhaust valves 15, 15' having stems 16, 16', are shown mounted in a similar manner in guide bearings 17, 17', and have springs 18 and 18' and tappets 19 and 19' to operate them in timed 20 and cooperative relation with inlet valve 5 and 5' to discharge the burned gases from chambers 10 and 10' through passage-ways 4, 4', and then through a usual exhaust manifold, muffler and discharge pipe to the outside air.

30 The valve structure above set forth is conventional and its known operation well understood. Lubrication of the moving valves is necessary, and the drawing shows oil apertures 20 in the cylinder block 2, through which oil is splashed, 35 as from the crank case, and contacts with the valve stems projecting below their guide bearings. The valve mechanism is ordinarily enclosed in a housing forming a lubricating chamber therefor, and whatever means are employed to supply it 40 with oil, or oil mist, the ordinary practice is to supply such lubricant to the stem projections, to be carried upward through their guide bearings to properly oil the reciprocated stems.

The above described means for oiling the inlet 45 valves and their stems have proved satisfactory due to the suction of each intake stroke of the cylinders creating suction in inlet passage-way 3, and such suction assists capillary attraction to draw oil upward in the guide bearings. In the 50 case of the exhaust valves however, the discharging burned gases cause a reversely directed pressure in the guide bearings for the exhaust valve stems, opposing the entry of oil thereto by stem reciprocation and capillary attraction, producing 55 inadequate lubrication. Lack of an oil film around such exhaust stems, not only produces friction and quick wear, but fails to seal the bearing and permits burnt gases to pass through the bearing into the valve chamber to quickly contaminate the oil supply therein. A film of oil 60 around the stem is also essential to act as a conductive medium to help cool the valve and its stem by carrying the heat to the cylinder block 2, cooled by a usual water jacket or radiating fins. Furthermore the discharging burned gases contain more or less unburned products and partially 65 burned oil that has passed by the usual piston rings, and such unburned products and partly burned oil form deposits on the exhaust valve 15 and 15' and their stems 16 and 16' and enter the upper parts of their guide bearings 17 and 17', and without provisions to remove them while still mobile, these deposits quickly cause complete 70 valve failure as hereinbefore set forth.

75 To overcome the above ineffective lubrication

of the exhaust valve stems, I employ the suction induced by the reciprocated pistons, and employ this suction to aid in drawing a film of oil into the guide bearing for such exhaust valve stem, to remove the exhaust deposits on the valve and 5 the upper end of its stem, and to cause a constant removal of such film when weakened or destroyed by the heat of the exhaust gases so as to maintain through lubrication and proper sealing of the guide bearing, and improved valve action with 10 longer periods between necessary engine overhaulings.

In employing this intake suction of the engine for the above stated purpose, I have shown in Fig. 1 a simple effective means consisting of suction passage-ways 25 and 25' connecting the inlet passage-way 3 to the respective bearings for valve stems 16 and 16', such passage-ways being readily provided as by the drilled holes shown in the cylinder block 2 extended through the guide 20 bearings to the respective stems.

These suction passage-ways 25 and 25' permit the suction at each intake stroke of the cylinders, to cause a partial vacuum in the guide bearings 17 and 17', to preferably at a point intermediate their length as shown, such partial vacuum tending to assist the flow of lubricant upward into the bearing from its lower end, and to draw down into the bearing at its upper end the exhaust deposits on stems 16 and 16' while 30 still mobile, and to cause such oil and deposits to pass through passage-ways 25 and 25' to be mingled with the intake charges of combustible gases passing to chamber 10 and 10' depending on which inlet take 5 or 5' is in open position. 35

The suction action of the intake through said passage-ways 25, 25' automatically acts to draw in a film of oil into the guide bearings 17 and 17', and aided by capillary attraction to hold the same therein until broken down by heat, 40 when it is drawn off into the intake system and mixed with the incoming fuel for combustion with the latter, new oil automatically entering the guide bearings as such exhausted oil is drawn off. A dry valve stem is very inefficient in transferring its heat to the guide bearing and cylinder block for cooling, and by maintaining a conductive film of oil surrounding said stems as above described, cooling of the stem and valves is greatly improved, and at the same time a more 50 accurate machine fit of the stem in its bearing may be employed giving better and more lasting operation. Sticking valves are also prevented as the exhaust deposits on the stems and upper parts of the guide stems are removed while still 55 mobile and passed back into the inlet charges before being burned into a hard residue by subsequent exhaust discharges. Also the film maintained in the guide bearing seals the same to prevent back pressure and oil contamination by 60 leakage of the exhaust fumes through the guide bearings into the valve chamber. And due to such improved lubrication of the exhaust valves the efficiency of the engine is greatly improved, 65 necessity for reconditioning materially lessened, and oil consumption reduced due to lack of contamination from exhaust fumes.

The guide bearings 17 and 17' mentioned above may be formed directly in the cylinder block 2, but are more commonly made, as shown, as separate parts secured to suitable apertures in the block 2. In Fig. 4, I have indicated a guide bearing 30 particularly adapted for my present purposes, and form the same with an annular external groove 31 communicating by means 75

of one or more apertures 32 with an interior spiral oil groove 33 in the bore of the bearing. The groove 31 is located above the shoulder 34 at a height to register with the suction passage-way formed in the cylinder block 2, so that when the guide bearing is employed as a repair replacement, said groove may register with the passage-way, indicated by dotted lines 35, without required necessity of positioning the same. 10 The oil groove 33 is not essential but is useful where extreme conditions are encountered to assist the entry of oil into the bearing, and such groove is preferably extended above the aperture 32 but short of the upper end of the bore, such 15 upper end facilitating removal of the exhaust deposit on the upper end of the valve stem. The depth of the groove may be used to control or meter the admission of oil to the bearing.

In Fig. 2 I have indicated an overhead type 20 of valved engine, showing the cylinder 40, and the valves 41 and 42 in the head 43, directly over the cylinder. Guide bearing 44 for the stem 45 of exhaust valve 42 is shown with aperture 46 communicating with passage-way 47 25 to admit intake suction to its inner bearing surface so as to lubricate stem 45 in the manner above set forth and with the aforesaid improvements and advantages.

Fig. 3 indicates a so-called F-head type of 30 valve arrangement, the exhaust valve 50 in this case having its stem 51 guided in bearing 52, and intake suction is provided for by means of a passage-way 53 cored in the engine block with an end connection, not shown, to some point 35 in the inlet passage-way or manifold, and individual branch passage-ways 54 from said passage-way 53 to the respective exhaust guide bearings 52. And it will be understood that other means than above disclosed, may be employed 40 to connect the guide bearing for the exhaust stems with the intake suction for the purpose above set forth. Also it will be understood that the guide bearings for the valve stems may be formed directly in the cylinder block, Fig. 1 indicating guide bearing 17' as part of the block 45 2. And the passage-ways from inlet passage-way to stem bearings may be in the form of a tube or conduit 55 passing through the usual water jacket, as shown in Fig. 3. The application 50 of my improvements is not limited to four cycle engines but may conceivably be applied to other engines having an intake exerting a suction.

From the foregoing description it is believed 55 the nature of my invention, its simple application to conventional engine construction, and its contribution to improved engine operation, will be readily understood. Also that the particular embodiment disclosed may be modified and changed without departure from my invention as defined 60 in the following claims.

What I claim is:

1. In an internal combustion engine having cylinder inlet and exhaust passage-ways and provided with poppet-valves and a lubricant supply chamber therefor, an exhaust-valve stem bearing having a bore-end thereof extended into said supply chamber and provided with a suction conduit extending from above said bore end to the inlet passage-way, whereby suction produced 70 by opening of the inlet valve acts to draw lubricant through said bore-end into said exhaust valve bearing.

2. In an internal combustion engine having cylinder inlet and exhaust passage-ways and 75 provided with poppet-valves and a lubricant sup-

ply chamber therefor, an exhaust-valve stem bearing having one end of the bore thereof arranged in communication with said supply chamber and the other end thereof in communication with the exhaust passage-way, an intermediate 5 portion of said bore being provided with a suction conduit extending to the inlet passage-way, whereby suction produced by opening of the inlet valve acts to draw therethrough lubricant from one bore end and exhaust stem-deposited products from the other bore end.

3. In an internal combustion engine having cylinder inlet and exhaust passage-ways and provided with poppet-valves and a lubricant supply chamber therefor, an exhaust-valve stem bearing 15 having a spiral groove in the bore thereof arranged in communication with said supply chamber and provided with a suction conduit extending to the inlet passage-way, whereby suction produced by opening of the inlet valve acts to 20 draw lubricant into said exhaust valve bearing.

4. In an internal combustion engine having cylinder inlet and exhaust passage-ways and provided with poppet-valves and a lubricant supply chamber therefor, an exhaust-valve stem bearing having one end of the bore thereof arranged in communication with said supply chamber and the other end thereof in communication with the exhaust passage-way, a spiral groove in said bore extended to said lubricant communicating end 30 and an intermediate portion being provided with a suction conduit extending to said inlet passage-way, whereby suction produced by opening of the inlet valve acts to draw therethrough lubricants from one bore end and exhaust stem-deposited 35 products from the other end.

5. An internal combustion engine comprising separate inlet and exhaust passage-ways, separate inlet and exhaust poppet-valves for the respective passage-ways, a housing for said valves 40 having a lubricant supply chamber, guide bearings for said valves having bearing bores for their respective valve stems extended into said lubricant supply chamber, and a suction conduit connecting the exhaust valve stem bearing bore 45 with the inlet passage-way adjacent the inlet valve, whereby suction produced by the opening of said inlet valve acts to draw lubricant from said supply chamber into said exhaust stem bearing bore. 50

6. In a multi-cylinder internal combustion engine having inlet and exhaust passage-ways provided with separate poppet valves controlling communication with the respective cylinders and lubricant supply chambers for the several valves, 55 guide bearings for the exhaust valves each having its bearing bore in communication at one end with a lubricating chamber and at its other end with the exhaust passage-way, and an intermediate portion of each bore being provided with a suction conduit extending to said inlet passage-way whereby suction produced by opening of the inlet valves acts to draw therethrough lubricant from one end of each bore and exhaust stem-deposited products from the other end of each 60 bore.

7. In a multi-cylinder internal combustion engine having inlet and exhaust passage-ways provided with separate poppet valves controlling communication with the respective cylinders and lubricant supply chambers for the several valves, 70 guide bearings for each exhaust-valve stem having a bearing bore extended into its lubricant supply chamber, and a common suction conduit extending from said inlet passage-way with sepa- 75

- rate branches therefrom to each exhaust valve stem bearing, whereby suction produced by opening of the inlet valves acts to draw lubricant into said exhaust valve bearing bores.
5. In an internal combustion engine having cylinder inlet and exhaust passage-ways and provided with poppet valves and a lubricant supply chamber therefor, an exhaust valve bearing comprising a removable guide for the valve stem provided with a bearing bore having a spiral groove in communication with said lubricant supply chamber and an aperture connecting said groove with an external groove encircling said guide, said encircling groove being adapted to register 10 with a suction conduit connecting it with the inlet passage-way, whereby suction produced by opening of the inlet valve acts to draw lubricant into said guide bearing bore.
9. A renewable bearing for the exhaust valve stems of internal combustion engines having inlet and exhaust passageways provided with poppet valves and a lubricant suction conduit

extending from said inlet passage-way to said exhaust valve bearing, comprising a removable guide member having an exterior encircling groove adapted to register with said lubricant suction conduit, an interior bearing bore having a lubricant admission end, and an aperture connecting said bearing bore and said exterior guide encircling groove. 5

10. A renewable bearing for the exhaust valve stems of internal combustion engines having inlet 10 and exhaust passage-ways provided with poppet valves and a lubricant suction conduit extending from said inlet passage-way to said exhaust valve bearing, comprising a removable guide member having an exterior encircling groove adapted to 15 register with said lubricant suction conduit, an interior bearing bore having a spiral oil groove therein extending inward from a lubricant admission bore end, and an aperture connecting an intermediate portion of said spiral groove with 20 said extension guide encircling groove.

WILLIAM B. ULLRICH.
